Primary Examiner — Darlington Ly(74) *Attorney, Agent, or Firm* — Chiesa Shahinian & Giantomaso PC(57) **CLAIM**

The ornamental design for a go kart, as shown and described.

DESCRIPTION

FIG. 1 is a perspective view of the go kart showing our new design;

FIG. 2 is a rear isometric view thereof;

FIG. 3 is a top view thereof;

FIG. 4 is a front view thereof;

FIG. 5 is a rear view thereof;

FIG. 6 is a left side view thereof;

FIG. 7 is a right side view thereof; and,

FIG. 8 is a bottom view thereof.

The broken lines in the drawings illustrate portions of the go kart that forms no part of the claimed design.
